UNITED STATES PATENT OFFICE.

MAURICE GOUDARD AND MARCEL MENNESSON, OF LEVALLOIS-PERRET, FRANCE.

CARBURETER.

1,149,908.

Specification of Letters Patent. Patented Aug. 10, 1915.

Application filed September 22, 1913. Serial No. 791,190.

To all whom it may concern:

Be it known that we, MAURICE GOUDARD and MARCEL MENNESSON, citizens of the French Republic, residing at 39 Rue Fouquet, Levallois-Perret, Seine, France, have invented certain new and useful Improvements in Carbureters; and we do hereby declare the following to be a full, clear, and exact description of the invention, such as will 10 enable others skilled in the art to which it appertains to make and use the same.

The invention relates to carbureters and refers to improvements in devices of the type in question which are more particularly applicable to carbureters for fixed motors, but which may be utilized in some cases 15 for motors of other descriptions.

The principal object of the invention is so to construct apparatus or devices of the kind in question, that they may regulate the motors or other engines to which they are attached, without it being necessary to employ additional devices for this purpose.

25 The invention consists generally in combining with apparatus of the kind in question one or more tubes, each adapted to form a nozzle, or some of which are adapted to form nozzles and in providing a well 30 which is in direct connection with the lower portion of the constant level chamber, into which well the lower end of the before-mentioned tube or tubes dip, and in providing means for causing the relative position 35 of the aforesaid lower or entry openings of the tube and of the level of the fuel in the well to vary as a function of the velocity of the motor or other engine to which the device is attached, which means may 40 be the suction produced in the aspirator tube by the motor or other engine. The constant level chamber fitted to the apparatus, and the reservoir for feeding such constant level chamber may be respectively, a simple 45 chamber (that is to say one unprovided with a float) under the influence of the suction of the motor, and a lower reservoir connected to the aforesaid simple chamber by means of a tube opening into the latter at 50 above the height at which the fuel therein is to be maintained.

The invention also includes, besides the principal arrangements just mentioned, certain other details of construction which will 55 be hereinafter more fully explained.

In order that the invention may be clearly

understood, we will now proceed to describe the same with reference to the accompanying drawing, which, however, merely shows certain typical methods of carrying the 60 same into effect.

Figure 1 is a diagrammatic section in a plane or planes containing the respective axes of the constant level chamber and the nozzle; the carbureter being in this case 65 fitted with a single nozzle and constructed according to the invention. Fig. 2 shows another form of carbureter, provided with a single nozzle and constructed according to the invention.

70 In constructing a carbureter according to the invention and as illustrated in the accompanying drawing at Fig. 1 *a* is the constant level chamber, *b* is a well which is in direct communication with the lower 75 portion of the said constant level chamber *a*. This well is of such depth that, when the fuel in the constant level chamber *a* is at its normal height there is no liability 80 of the said fuel overflowing the edges of the well.

c is the aspirator tube.

d is a tube constituting a nozzle, the lower end of such tube being adapted to dip into the said well *b*, and the upper portion opening 85 into the aspirator tube *c*.

*d*¹ is a fine perforation in the tube *d*, which perforation may be located at the upper or lower portion of the said tube or in some other suitable position.

90 Means are provided for varying the relative positions of the entry orifice of the tube *d* and of the level of the fuel in the well *b*, as a function of the velocity of the motor or other engine. This means may be the suction produced in the aspirator tube *c* by the motor or other engine in connection therewith. The aforesaid means may comprise a device for causing the tube *d* to be displaced vertically while the level of the 100 fuel in the well *b* remains constant and may consist, as shown at Fig. 1, of an elastic diaphragm *e* which is so fitted and arranged that it is subjected on one of its faces to the atmospheric pressure and upon the other 105 face to the suction produced in the said tube *c*. The nozzle *d* is so attached to the said diaphragm, for instance by passing it through the said diaphragm and fixing it thereto that the tube itself is raised and depressed to a greater or less extent as a function of the suction produced in the said

110

tube. It may cease to dip into the fuel altogether when the velocity of the motor attains or passes a certain maximum, that is to say when the suction in the tube *s* exceeds a certain amount.

As an alternative means may be employed for modifying the height of the level of the fuel in the well *b* while the tube *d* remains immovable. For instance and as shown at Fig. 2, a conduit *f* may be provided, the sectional area of which may be capable of regulation, which conduit is so arranged as to establish a communication between the aforesaid tube *c* and the upper portion of the constant level chamber *a*, the said chamber being either made air tight or provided with a perforated cover furnished with means such as a small opening *g*, (Fig. 2) for establishing a communication between the interior of the said chamber and the atmosphere. The opening *g* may be so formed that its dimensions can be regulated. In other cases means may be provided for enabling the tube *d* to be vertically displaced and for modifying the height of the fuel in the well *b* at the same time.

With this construction when the motor to which the carbureter is fitted is working normally, the nozzle of the carbureter acts in the ordinary manner, while when the speed of the motor rises, the relative positions of the entry orifice of the tube *d* and of the surface of the fuel in the well *b* is modified, owing to the increase of suction produced in the upper portion of the constant level chamber *a*. The extent to which the said opening dips beneath the surface of the fuel in the said well consequently diminishes, until it entirely disappears or even becomes negative. The supply of fuel to the nozzle therefore diminishes to a greater and greater extent until it is entirely cut off when the level of the fuel in the well falls below the entry orifice of the tube *d*. This occurs when the maximum velocity selected has been reached, the extent to which the tube *d* dips into the well *b* being regulated accordingly, as shown in the example at Figs. 1 and 2.

We may combine, with the foregoing arrangements, one of the ordinary systems usually employed for regulating the speed of fuel to the constant level chamber *a*.

It will be understood that the invention is not limited in any way to the particular method of carrying it into effect which has been more particularly described with reference to the drawing, but that it includes all modifications falling within the principle thereof.

What we claim and desire to secure by Letters Patent of the United States of America is:

1. In a carbureter the combination of a

constant level chamber, a well in direct communication with said chamber and subject to atmospheric pressure at the top thereof, a tube forming a nozzle the lower end of which tube is adapted to dip into the fuel in the well and means for modifying as a function of the velocity of the motor to which the device is attached the extent of immersion of the lower orifice of the tube in the fuel in the well substantially as described. 70 75

2. In a carbureter the combination of a constant level chamber, a well in direct communication with said chamber and subject to atmospheric pressure at the top thereof, a tube forming a nozzle the lower end of which tube is adapted to dip into the fuel in the well and means controlled by the suction produced in the aspirator tube connecting the carbureter and the motor for modifying as a function of the velocity of the motor to which the device is attached the extent of immersion of the lower orifice of the tube in the fuel in the well substantially as described. 80 85 90

3. In a carbureter the combination of a constant level chamber, a well in direct communication with said chamber and subject to atmospheric pressure at the top thereof, a tube forming a nozzle the lower end of which tube is adapted to dip into the fuel in the well, and means controlled by the suction produced in the aspirator tube connecting the carbureter and the motor to which the device is attached for relatively varying the level of fuel in the well with respect to the lower end of the nozzle to an extent proportional to the velocity of the motor substantially as described. 95 100 105

4. In a carbureter the combination of a constant level chamber, a well in direct communication with said chamber and subject to atmospheric pressure at the top thereof, a tube forming a nozzle the lower end of which tube is adapted to dip into the fuel in the well, and means exposed to the suction of the motor to cause the relative height of the level of fuel in the well and the lower end of the nozzle to rise and fall to an extent proportional to the velocity of the motor substantially as described. 110 115 120

5. In a carbureter, the combination of a constant level chamber, a well in direct communication with the said chamber, a tube forming a nozzle, the lower end of which tube is adapted to dip into the fuel in the well, means controlled by the suction produced in the aspirator tube connecting the carbureter and the motor to which the device is attached, for causing the nozzle to be displaced vertically, means for causing the suction produced in the said aspirator tube to be communicated to the surface of the fuel in the constant level chamber so that the depth to which the lower end of the tube 130

dips into the fuel in the well varies proportionately to the velocity of the motor substantially as described.

6. In a carbureter, the combination of a constant level chamber, a well in direct communication with the said chamber, a tube forming a nozzle, the lower end of which tube is adapted to dip into the fuel in the well, and the upper end of which is exposed to the suction of the engine, and means for causing the suction produced in the said aspirator tube to be communicated to the surface of the fuel in the constant level chamber so that the depth to which the lower end of the tube dips into the fuel in the well varies proportionately to the velocity of the motor substantially as described.

7. In a carbureter, the combination of a constant level chamber, a well in direct communication with the said chamber, a tube forming a nozzle, the lower end of which

tube is adapted to dip into the fuel in the well, and the upper end of which is exposed to the suction of the engine, means for causing the suction produced in the said aspirator tube to be communicated to the surface of the fuel in the constant level chamber so that the depth to which the lower end of the tube dips into the fuel in the well varies proportionately to the velocity of the motor, 25 and an opening the size of which may be regulated between the atmosphere and the top of the space in the constant level chamber substantially as described.

In testimony whereof, we affix our signatures, in presence of two witnesses.

MAURICE GOUDARD.
MARCEL MENNESSON.
